UNITED STATES PATENT OFFICE

JOHN WILLIAM HARTLEY, OF STONE, ENGLAND

MOLDING AND THE FORMING OF SAND MOLDS

Application filed September 9, 1932, Serial No. 632,309, and in Great Britain September 24, 1931.

This invention relates to molding and the forming of sand molds.

The object of the invention is to enable molds for many articles to be more rapidly formed in sand or other suitable medium with less labour than heretofore.

A further object of the invention is to permit of chilled surfaces being readily formed upon the castings.

10 A further object of the invention is to dispense with the mold boxes or snap flasks at present used for holding each individual sand mold during the molding operation.

15 A further object of the invention is to economize in floor space.

Referring to the drawings which form a part of this specification:

Figure 1 is a side elevation of part of a platform and a mold-box adapted to travel 20 along it.

Figure 2 is a plan thereof.

In Figures 1 and 2 a length of the platform is broken away to facilitate illustration.

Figure 3 is an elevation of a further length 25 of the platform showing also a travelling table to be hereinafter referred to.

Figures 4 and 5 are elevations of the travelling mold-box drawn to an enlarged scale and illustrating two forms of mechanism for pushing off a detachable side from the mold-box, such mechanism being omitted from Figures 1 and 2 for the sake of clarity in illustration.

35 Figure 6 illustrates a detail to be referred to.

On the floor of the foundry or the like a series of plates 10 are supported by an under-frame 11 to form a flat level working surface; the top and bottom surfaces and the edges of the plates are machined so that the plates may be reversed and both surfaces used, and the edges of the plates used for guiding the mold box 13. A transverse fence or angle plate 12 is provided near one end of the series of plates 10. The sand or mold box is in the form of a rectangular open-topped and open-bottomed framing 13 having slightly tapered ends, one side 13^a being loose or removable and secured in position by catches or clamps 14 so that it can be

readily detached when required. This side 13^a has projecting ends which fit closely and embrace the ends of the open side of the box 13. To the interior of this side of the box is secured a half pattern or patterns, and a further corresponding half pattern or patterns is secured to the interior of the opposite side of the box. The box 13 is slideable along the plates 10. In filling sand into the box a hopper is placed over the top thereof and the sand rammed down about the pattern in the usual manner until the box is full. The hopper is then removed, the clamps 14 disengaged and the side 13^a detached. The sand mold is then pushed along the plates 10 up to the fence 12, thus wasting one half of the first sand mold formed; the box is then withdrawn, the side 13^a replaced and sand rammed in again; the second sand mold is then, after removing the side 13^a, pushed 60 up to the first one; a complete sand mold is thus formed between the two blocks of sand, and a half mold is left on the second block for the third to fit up to, the process being 65 repeated as required until the plates 10 are 70 covered with sand molds. The mold box is slid along the plates 10 by a carriage 15^a having flanged runner wheels 15 riding on and engaging with the edges of said plates, whilst pinions 16 gearing with racks 17 ensure the 75 parallel travel of the mold box. Plates 18 serve as dust shields for the bearings of the wheels 15. A travelling table 19 Figure 3 is provided which runs on the racks 17 and carries the sand hopper, loose hand tools, and also lifting gear 27 and a counterweight 28 for lifting or removing the side 13^a from the box after it has been released; it may also carry a molten metal hopper for guiding the 80 molten metal when casting into the sand molds. The loose side 13^a of the mold box, as shown in Figure 4, is adapted to be pushed away from the box on the release of the securing clamps aforesaid by push rods 20 operated by cranks 21 at each end of a horizontal cross shaft 22 carrying an operating handle 23, preferably at or about its centre; or, as shown in Figure 5, a sliding rack 24 may be substituted for the push rods, pinions 85 90 95 25 being provided one at each end of the 100

shaft 22, the shaft 22 being operated by a reversible ratchet and pawl instead of the fixed handle 23 shown in Figure 4.

The surface of the plates 10 is used to form the bottom of the mold in cases where a chilled surface is required, the surface of the molded article exposed to the plates being chilled by said plates and the remainder of the molded article being formed in the sand of the mold. If the castings are not to be chilled the patterns are raised above the plates 10 so that sand may be rammed beneath them; the depth of the mold box may be increased so that when rammed up full with sand there is sufficient body of sand above the pattern to provide runners for the head of metal required for the pattern. Where patterns are flat on one side the pattern or patterns is or are preferably not secured to the loose side 13^a of the box but to the main fixed portion thereof; the joint between successive sand molds in this case is not in the centre of the pattern as previously described but upon the plain face of the loose side which forms the flat sand face of the mold and also the joint. In an alternative or additional method of ensuring the correct alignment of the travelling mold box, guides may be attached to the ends of the box and also to the loose side adapted to engage with the edges of the plates as the mold box slides along the guides being preferably in the form of rollers 26, 26^a, Figures 5, 6, one 26 rigidly mounted and the other 26^a being under the control of a spring 26^b incorporated in the bracket tending to keep it in contact with the edge of the plates.

The runner wheels of the travelling table 19 may, by making the mold box 13 and fence 12 slightly narrower, travel along the edges 40 of the plates, or upon separate rails, instead of along the racks 17.

The molds may be rammed up by any well known method of ramming and the sand may be slung into the mold box by any well known method of sand slinging; a ramming appliance may be attached to the travelling table 19 to ram the sand either by hand or other power. A portable hydraulic, pneumatic or other device may be used for squeezing or pressing the mold box horizontally inwards similar in action to a portable riveter when closing a rivet, such device being conveniently carried by or from the table 19 or upon the racks or rails alongside the platform.

Having now described my invention, what I claim as new and desire to secure by Letters Patent is:—

1. Apparatus for use in molding and the forming of sand molds comprising a flat level working surface, an open-bottomed mold-box movable along said surface, and a removable side to said mold-box, said mold-box being adapted to have sand molds formed therein, to carry such sand molds to

an appropriate position on the working surface, and on the detachment of the removable side to deposit such molds adjacent each other ready to receive the molten metal.

2. Apparatus for use in molding and the forming of sand molds comprising a flat level working surface, an open-bottomed mold-box movable along said surface, a removable side to said mold-box, and ends on said mold-box tapered internally, said taper facilitating the withdrawal of the box from around the sand mold after the detachment of said removable side. 70 75

3. Apparatus for use in molding and the forming of sand molds comprising a flat level working surface, an open-bottomed mold-box movable along said surface, a removable side to said mold-box, and securing elements on said mold-box, said elements being adapted to hold said removable side in position. 80 85

4. Apparatus for use in molding and the forming of sand molds comprising a flat level working surface, an open-bottomed mold-box, movable along said surface, a removable side to said mold-box, internally tapered ends on said mold-box, and securing elements on said mold-box for said removable side. 90 95

5. Apparatus for use in molding and the forming of sand molds comprising a flat level working surface, an open-bottomed mold-box movable along said surface, a removable side to said mold-box, and means operative in moving said removable side from contact with the sand in said mold-box when required. 100

6. Apparatus for use in molding and the forming of sand molds comprising a flat level working surface, an open-bottomed mold-box movable along said surface, a removable side to said mold-box, means operative in moving said removable side from contact with the sand in said mold-box, internally tapered ends on said mold-box, and securing elements on said mold-box for said removable side. 105 110

7. Apparatus for use in molding and the forming of sand molds comprising a flat level working surface, an open-bottomed mold-box movable along said surface, a vertical fence member extending upwardly from said surface and adapted to receive the first of a series of molds formed in said mold-box against one of its faces, and a removable side to said mold-box. 115 120

8. Apparatus for use in molding and the forming of sand molds comprising a flat level working surface, a vertical fence member extending upwardly from said working surface, an open-bottomed mold-box movable along said surface, a removable side to said mold-box, internally tapered ends on said mold-box, and securing elements on said mold-box for said removable side. 125

9. Apparatus for use in molding and the 130

- forming of sand molds comprising a flat level working surface, a vertical fence member extending upwardly from said working surface, an open-bottomed mold-box movable along said surface, pinions associated with said mold-box and racks therefor at the sides of said working surface, a removable side to said mold-box, internally tapered ends on said mold-box, securing elements on said mold-box, and aligning devices for said removable side.
- 5 10. Apparatus for use in molding and the forming of sand molds comprising a flat level working surface, an open-bottomed mold-box movable along said surface, a removable side to said mold-box, pinions associated with said mold-box, and racks at the sides of said working surface, said pinions being arranged to travel on said racks and so ensure the parallel travel of the mold-box.
- 15 20. 11. Apparatus for use in molding and the forming of sand molds comprising a flat level working surface, an open-bottomed mold-box movable along said surface, pinions associated with said mold-box and racks therefor at the sides of said working surface, a removable side to said mold-box, internally tapered ends on said mold-box, securing elements on said mold-box for said removable side and means operative in moving said removable side from contact with the sand in said mold-box.
- 25 30. 12. Apparatus for use in molding and the forming of sand molds comprising a flat level working surface, a vertical fence member extending upwardly from said working surface, an open-bottomed mold-box movable along said surface, pinions associated with said mold-box and racks therefor at the sides of said working surface, a removable side to said mold-box, internally tapered ends on said mold-box, securing elements on said mold-box for said removable side and means operative in moving said removable side from contact with the sand in said mold-box.
- 35 40. 13. Apparatus for use in molding and the forming of sand molds comprising a flat level working surface, an open-bottomed mold-box movable along said surface, a removable side to said mold-box, and aligning devices adapted to ensure the correct alignment of the mold-box along the working surface.
- 45 50. 14. Apparatus for use in molding and the forming of sand molds comprising a flat level working surface, an open-bottomed mold-box movable along said surface, pinions associated with said mold-box and racks therefor at the sides of said working surface, a removable side to said mold-box, internally tapered ends on said mold-box, securing elements on said mold-box for said removable side, means operative in moving said removable side from contact with the sand in said mold box, and aligning devices for said mold-box.
- 55 60. 15. Apparatus for use in molding and the forming of sand molds comprising a flat level
- working surface, a vertical fence member extending upwardly from said working surface, an open-bottomed mold-box movable along said surface, pinions associated with said mold-box and racks therefor at the sides of said working surface, a removable side to said mold-box, internally tapered ends on said mold-box, securing elements on said mold box for said removable side, means operative in moving said removable side from contact with the sand in said mold box, and aligning devices for said mold-box.
- 65 70. 75. 80. 85. 90. 95. 100. 105. 110. 115. 120. 125. 130.
